(57) **CLAIM**

The ornamental design for a planter for steps, as shown and described.

DESCRIPTION

FIG. 1 is a top front and left side perspective view of a first embodiment of a planter for steps showing my new design; FIG. 2 is a top plan view thereof;

FIG. 3 is a front view thereof;

FIG. 4 is a left side view thereof;

FIG. 5 is a right side view thereof;

FIG. 6 is a rear view thereof; and,

FIG. 7 is a top plan view of a second embodiment, the front, left side, right side and rear views are mirror images of corresponding sides of the first embodiment.

The broken lines shown in FIG. 1 form no part of the claimed design and are for environmental purposes only.
